UNITED STATES PATENT OFFICE

2,251,030

PORTABLE POWER-DRIVEN METAL ROLLER

Edgar Clay Blevins, Princeton, W. Va.

Application November 16, 1939, Serial No. 304,854

6 Claims. (Cl. 153—48)

This invention relates to a portable power-driven metal roller particularly adapted for straightening or removing the dents from the fenders, bodies or other metal surface of automobiles.

It is an object of the invention to provide a tool of the above-mentioned character which includes a dolly in cooperative relation to a reciprocating roller and means for manually adjusting the dolly to regulate the pressure of the same against the work.

A further object of the invention resides in providing a device of the above-mentioned character which is simple and durable in construction, reliable and efficient in operation, and inexpensive to manufacture.

Other objects and advantages of the invention will be apparent during the course of the following description.

In the accompanying drawing forming a part of this specification, and in which like numerals are employed to designate like parts throughout the same:

Fig. 1 is a side elevation of the tool.

Fig. 2 is a longitudinal section of the housing showing the driving mechanism for the roller, and

Fig. 3 is a vertical section taken on line 3—3 of Fig. 1.

In the drawing, wherein for the purpose of illustration I have shown a preferred embodiment of the invention, the numeral 5 denotes an elongated hollow casing having its forward end bifurcated to form a slot 6 adapted to slidably receive the cross head 7. The sides of the slot are provided with dovetail shaped ribs 8 which engage in correspondingly shaped grooves 9 in the sides of the cross head to guide the movement of the cross head when reciprocated. A plate 10 extends across the end of the slot 6 which limits the forward movement of the cross head. A fork 11 depends from the cross head to support the roller 12 which is journaled in the fork by the shaft 13. A connecting rod 14 extends longitudinally of the casing 5 having one end pivotally connected to the cross head 6, as at 15, and its opposite end connected to the drive gear 16 by the eccentric 17. The drive gear 16 is mounted on the shaft 18 and is in mesh with the worm 19 on the shaft 20 which through bevel gears 21 and 22 is connected to the shaft 23 of the electric motor 24 mounted in the housing 25 formed integral with the casing 5. The starting and stopping of the motor is controlled by an electric switch 26.

A hand rest 27 is mounted in straddling relation to the casing 5 having ears 28 extending along the sides of the casing and pivotally connected thereto by pivot pins 29. The ears 28 are pivotally connected by links 30 to the forward end of the rocker member 31 which is pivotally suspended beneath the rear end of the casing 5 by ears 32 pivotally attached to the sides of the casing by pivots 33. The rear end of the rocker member 31 is provided with a socket 34 to receive one end of the C arm 35 which is secured in the socket by a set screw 36. The free end of the arm 35 is disposed beneath the path of movement of the roller 12 and is provided with a socket 37 adapted to slidably receive the bearing block 38 which pivotally supports the dolly 39 for cooperative action with the roller 12. A heavy coil spring 40 disposed in the socket 37 beneath the bearing block 38 yieldably supports the dolly in a raised position, and it will be seen the dolly is free to move in the direction of travel of the roller. The dolly is interchangeably mounted so that different shaped dollies may be used for performing work of various kinds.

In operation, the work is inserted between the roller 12 and dolly 39 and upon starting the motor 24 the drive gear 16 is rotated to impart a reciprocating movement to the connecting rod 14, thus reciprocating the cross head 7 in the slot 6 to move the roller 12 back and forth across the work. By pressing down on the hand rest 27 the rocker member 31 is actuated to swing the arm 35 so the pressure of the dolly 39 against the work may be regulated. The tool being light in construction may be easily ported from place to place, and in practice it is found sheet metal parts of an automobile may be easily and efficiently worked upon to remove dents and other irregularities without the exercise of more than ordinary mechanical skill.

It is to be understood that the form of my invention herein shown and described is to be taken as a preferred example of the same, and that certain changes in the shape, size, and arrangement of the parts may be made without departing from the spirit of the invention or the scope of the subjoined claims.

Having thus described my invention, I claim:

1. A portable metal rolling tool comprising an elongated casing forming a hand grip, a cross head mounted to reciprocate longitudinally in said casing, a roller suspended from said cross head, an arm pivotally connected to the inner end of said casing having its free end disposed beneath the path of movement of said roller,

a dolly supported by the free end of said arm for cooperative action with said roller, means for reciprocating said cross head, and means for swinging said arm to move said dolly towards and from said roller.

2. A portable metal rolling tool comprising an elongated casing forming a hand grip, a cross head mounted to reciprocate longitudinally in said casing, a roller suspended from said cross head, an arm pivotally connected to the inner end of said casing having its free end disposed beneath the path of movement of said roller, a dolly supported by the free end of said arm for cooperative action with said roller, a hand lever mounted on said casing for moving said arm to move said dolly towards and from said roller, and means for reciprocating said cross head.

3. A portable metal rolling tool comprising an elongated casing forming a hand grip, a cross head mounted to reciprocate longitudinally in said casing, a roller suspended from said cross head, means for reciprocating said cross head, an arm pivotally connected to the inner end of said casing having its free end disposed beneath the path of movement of said roller, a dolly pivotally mounted in the free end of said arm for cooperative action with said roller, yieldable means normally urging said dolly towards said roller, and means for swinging said lever to move the free end towards and from said roller to control the pressure of said dolly.

4. A portable metal rolling tool comprising an elongated casing forming a hand grip, a cross head mounted to reciprocate longitudinally in said casing, a roller suspended from said cross head, means for reciprocating said cross head, a rocker member pivotally attached to the inner end of said casing, an arm having one end attached to said rocker member and its free end disposed for movement towards and from said roller, a dolly yieldably mounted in the free end of said arm for cooperative action with said roller, and a hand lever pivotally mounted on said casing having connection with said rocker member for actuating said member to swing

said arm to control the pressure of said dolly.

5. A portable metal rolling tool comprising an elongated casing forming a hand grip, a reciprocating cross head mounted in one end of said casing, a roller suspended from said cross head, means for reciprocating said cross head, a rocker member pivotally attached to said casing, a C arm having one end attached to said rocker member and its free end disposed for movement towards and from said roller, a bearing block yieldably mounted in the free end of said arm for vertical movement, a dolly pivotally mounted in said bearing block for swinging movement in the direction of travel of said roller, a hand lever pivotally mounted on said casing, and links connecting said hand lever to said rocker member whereby the rocker member is actuated by said hand lever to swing said arm to adjust the pressure of said dolly.

6. A portable metal rolling tool comprising an elongated tubular casing forming a hand grip, said casing being bifurcated at its forward end to receive a slidably mounted cross head, a roller suspended from said cross head, mechanism within said casing for imparting a reciprocating movement to said cross head, a rocker member pivotally mounted intermediate its ends to the underside of the rear end of said casing, a C arm having one end fixedly attached to one end of said rocker member and its opposite end disposed beneath the path of movement of said roller and movable towards and from said roller, a bearing block slidably mounted in the free end of said arm for vertical movement, a spring mounted beneath said bearing block yieldably supporting said bearing block in a raised position, a dolly pivotally mounted in the top of said bearing block extending upwardly therefrom, a hand lever pivotally mounted on the upper side of said casing, and links connecting one end of said hand lever to the end of said rocker member whereby the rocker member is actuated by said hand lever to swing said arm to adjust the pressure of said dolly.

EDGAR CLAY BLEVINS.
